UNITED STATES PATENT OFFICE

JAMES F. ALLISON, OF PROVIDENCE, RHODE ISLAND, ASSIGNOR TO FREEMAN-DAUGHADAY COMPANY, A CORPORATION OF MASSACHUSETTS

COLLAR HOLDER

Application filed November 21, 1930. Serial No. 497,148.

This invention relates to a holder for soft collars, and has for its object to provide jaws which may be more easily moved to grip the flap of the collar and yet which will maintain the same securely in frictional engagement therewith due to the inherent resiliency of the stock of which it is made.

Another object of the invention is the provision of means for increasing the frictional surface engagement upon the fabric of the collar to better hold the same in engagement therewith without causing more difficult engagement of the jaws with the fabric.

A further object of the invention is the provision of means and method of mounting an anti-friction roller in one of the jaws without the use of a separate axle pin.

A still further object of the invention is the provision of integral means for forming a pivot for the rotatable member from the stock of one of the jaws thereof.

With these and other objects and advantageous features in view, the invention consists of a novel arrangement of parts more fully disclosed in the detailed description following, in conjunction with the accompanying drawings, and more particularly set forth in the appended claims.

In the drawings:

Fig. 1 is a top plan view of a collar holder;
Fig. 2 is a side elevation thereof;

Fig. 3 is a side elevation of the member forming the upper jaws;

Fig. 4 is a perspective view of the anti-frictional roller;

Fig. 5 is a section on line 5—5 of Figure 2;
Fig. 6 is a section on line 6—6 of Figure 2;

Fig. 7 is an enlarged view of a fragmental portion of one of the jaw members showing the same as blanked from sheet stock for the rotatable member mounted therein;

Fig. 8 is a view similar to Figure 7 showing the anti-friction roller as mounted in position.

In the use of collar holders, a certain friction must be maintained between the gripping jaws by inherent resiliency of the stock to hold the same in position on the flap of the collar; the desirable friction is frequently of such extent as to make it diffi-

cult to position the jaws upon the collar; and in order that the jaws may be of sufficient stiffness to provide a firm frictional grip on the flap of the collar and at the same time provide a structure by which the jaws may be easily positioned in place, I have mounted a roll or anti-friction member which will revolve about its axis in sliding the jaws along the collar to grip the same and thus permit by this rolling action an easier mounting of the same in position; and the following is a detailed description of the present embodiment of this invention, illustrating the preferred means by which these advantageous results may be accomplished.

With reference to the drawings, 10 designates the outer or top member of the holder which is generally triangular in cross-section throughout its length, as illustrated in Figure 6. An inner or back member 11 is of flat sheet stock such as is illustrated in Figures 6, 7 and 8. These two members are bent intermediate their ends to provide offset portions 12 in the member 11 which contact a substantial distance along their offset portions, and about which a band 14 is provided to securely hold the two members in position providing jaws 15 on the outer member and 16 on the back or inner member arranged in oppositely extending pairs between which the fabric of the outer flaps of the collar may extend to be engaged.

In order that the jaws may be more easily slid upon the fabric in manufacture, I cut out a portion of the lower jaw to provide a recess 17 therein, the recess being shaped to provide oppositely inwardly extending trunnions 18. A roll 19 of generally cylindrical shape has an opening 20 therein, into which these trunnions may be forced by squeezing the opposite sides 21 along the opening toward each other to rotatably mount the roll 19 therein. This roll is corrugated as at 22 to better grip the fabric and have rolling engagement therewith. The jaw 15 of the device is recessed at 23, to receive the roll 19 and increase the frictional engagement of the same with the jaw and at the same time cause the same to lie closer against the fabric and increase its frictional

engagement therewith for holding the same in position.

By these means, the collar holder may be easily slid onto the fabric and be securely held by the inherent resiliency of the opposite jaws to hold the collar in the desired position on the user.

While I have described certain construction forms which embody the principles of my invention, it is obvious that other desired changes in arrangement may be made within the spirit and the scope of the invention as defined in the appended claims.

I claim:

15. 1. A collar holder having oppositely disposed pairs of jaws with one of the jaws resilient, one of said jaws having an anti-friction member mounted therein for rolling contact with the fabric inserted into said jaws.
20. 2. A collar holder having oppositely disposed pairs of jaws, one of said jaws having a recess therein, an anti-friction member mounted in said recess for rolling contact with the fabric inserted into said jaws.
25. 3. A collar holder having oppositely disposed pairs of jaws, one of said jaws having a recess therein, an anti-friction member in said recess, and trunnions extending into said recess for rotatably mounting said member.
30. 4. A collar holder having oppositely disposed pairs of jaws, one of said jaws having an opening therein, a roller in said opening contacting with the opposite jaw for rolling contact with the fabric inserted between the jaws.
35. 5. A collar holder having oppositely disposed pairs of jaws, one of said jaws having an opening therein, a roller in said opening contacting with the opposite jaw for rolling contact with the fabric inserted between the jaws, and integral extensions projecting into said opening for rotatably mounting said roll.
40. 6. A collar holder having oppositely disposed pairs of jaws, one of said jaws having an anti-friction member mounted therein for rolling contact with the fabric inserted into said jaws and the other of said jaws having a recess to receive said anti-friction member.
45. 7. A collar holder having oppositely disposed pairs of jaws, a roll mounted on one of said jaws and contacting with said opposite jaw, one of said jaws being resilient to permit the fabric to be inserted between said points of contact.
50. 8. A collar holder having oppositely disposed pairs of jaws, a roll mounted on one of said jaws and contacting with said opposite jaw, said opposite jaw having a recess to receive said roll contacting therewith.
55. 9. A collar holder having oppositely disposed jaws, and a roll mounted in one of said jaws against axial displacement having a sur-

face for rolling contact with the fabric inserted between said jaws.

10. A collar holder comprising a pair of members offset at their center portions and arranged to have their offset portions contact, means for securing said offset portions together to provide oppositely extending pairs of jaws, a pivotally mounted roll in one jaw of each pair for contact with the opposite jaw, whereby to have rolling contact with the fabric inserted thereinto.

11. A collar holder comprising a pair of members offset at their center portions, contact means for securing said offset portions together and providing oppositely extending pairs of jaws, a pivotally mounted roll in one jaw of each pair for contact with the opposite jaw, whereby to have rolling contact with the fabric inserted thereinto, said opposite jaw of each pair being arcuately recessed to receive said roll.

12. A collar holder comprising a pair of members offset at their center portions, means for securing said offset portions in contiguous relation and providing oppositely extending pairs of jaws, a pivotally mounted roll in one jaw of each pair for contact with the opposite jaw, whereby rolling contact is provided with the fabric inserted thereinto, said roll being corrugated on its surface, and said opposite jaw of each pair being arcuately recessed to receive said roll.

In testimony whereof I affix my signature.
JAMES F. ALLISON.
